ELEVATOR

John T. Austin, Hartford, Conn.

Application August 3, 1934, Serial No. 738,237

7 Claims. (Cl. 187—16)

The present invention relates to the transportation of vehicles, elevator cars or the like in shafts which are disposed at an angle greater than the angle at which a vehicle such as an automobile, will climb with friction due to its own weight. Heretofore, it has been the practice in the elevator art, for example, to provide a shaft, and a single car in the shaft movable up and down therein, an arrangement which is very inefficient and one which requires a relatively large number of elevator shafts in high buildings.

The aim of the present invention is to provide an improved arrangement wherein a number of cars may be moved in any desired sequence and in succession up or down the elevator shaft, as the case may be, so that the number of shafts required is reduced to a minimum, thus effecting a saving in floor space, a factor which is of prime importance, particularly in high buildings.

A further aim of the invention is to provide an improved arrangement of this sort wherein the number of cars in use may be varied to suit requirements, thus giving flexibility in service, the arrangement being such that additional cars may be brought into service as desired, and when the traffic decreases, some of the cars may be temporarily taken out of use.

A further object of the invention is to provide an improved arrangement which is relatively simple, which requires a small amount of space, which is efficient in operation, and which may be easily installed.

In accordance with the disclosure of the present invention, the opposite sides of the shaft are provided with a plurality of opposed tracks, the cars are provided at opposite sides with wheels or rollers maintained in firm engagement with the respective opposed tracks, and operating means are provided on the cars for driving the wheels. Preferably, the wheels are provided with resilient tires; for example, rubber pneumatic tires, and means are provided on the cars for urging the tires into frictional engagement with the opposed tracks. The number of shafts, of course, will depend upon requirements. If desired, two shafts may be used, one an "up" shaft and one a "down" shaft, and in higher buildings, there may be provided an "up" shaft, a "down" shaft, and an "up and down" express shaft.

Other objects will be in part obvious, and in part pointed out more in detail hereinafter.

The invention accordingly consists in the features of construction, combination of elements, and arrangement of parts which will be exempli-

fied in the construction hereinafter set forth and the scope of the application of which will be indicated in the appended claims.

In the accompanying drawings, wherein is shown, for illustrative purposes, one embodiment which the present invention may take,

Fig. 1 is a view partly in section and partly in elevation of my improved device;

Fig. 2 is an enlarged fragmentary view of the same;

Fig. 3 is a horizontal transverse section of one of the shafts and looking down upon a car therein;

Fig. 4 is a front elevation of the carrier and a portion of the transfer mechanism;

Fig. 5 is a top plan view of what is shown in Fig. 4;

Fig. 6 is a front elevation of the transfer mechanism;

Fig. 7 is an elevational view of the lower portion of a cage and car therein, the cage being provided with means whereby it may be driven in a horizontal plane; and

Fig. 8 is a diagrammatic view of a hill or mountain provided with shafts of various levels in which a car is adapted to travel.

Referring to the drawings, and particularly to that embodiment shown in Figs. 1 to 6, wherein the invention is shown as embodied in an elevator for a building or the like, A generally designates an "up" shaft, B a "local down" shaft, C an "express up and down" shaft. D generally designates the cars adapted to travel in said shafts, and E transfer mechanisms for cages or transfer carriers G which may be located at the bottom and top of the shafts, as hereinafter described more in detail.

While three shafts are shown in Fig. 1, two, four, or any other number of shafts may be employed. Each of these shafts A, B and C is disposed in a substantially vertical position in a building F or the like, a portion only of which is shown. Each shaft comprises a front wall 10, a rear wall 11 and opposed side walls 12. The side walls 12 of each shaft have secured thereto in opposed relation a plurality of spaced apart parallel tracks or rails 13. These tracks may be in the form of I-beams, any desired number of which may be provided, and they may be secured to their respective side walls 12 by bolts or other suitable fastening means, not shown. These shafts may be made of any desired height and the tracks are of a corresponding height.

Each car D may be constructed of any suitable material and of any desired size, but is pref-

erably made as light as is consistent with strength and safety. Each car D includes a top 14, a bottom 15 and a pair of doors 16 of the usual construction.

5   Mounted on the top 14 of each car are two pairs of brackets 18. A shaft 19 is rotatably supported by each pair of brackets, and keyed to each shaft 19 so as to rotate therewith is a plurality of wheels 20 upon each of which is mounted a rubber tire 21. The wheels 20 preferably correspond to the number of tracks 13. A worm wheel 22 is keyed or otherwise fixed to each shaft 19, and each worm wheel meshes with a worm 23 fixed to the opposite ends of a drive shaft 24 which is driven by a light high speed electric motor 25 mounted upon the top 14 of the car D. The brackets 18 on the left-hand side of the car looking at Fig. 2 are fixed to the car while the right-hand brackets have sliding movement towards the adjacent tracks 13 in suitable guides 26 fixed in any appropriate manner to the top of the car.

20   Springs 27 are confined respectively between flanges 28 on the right-hand brackets 18 and 25 abutments 29 fixed to the top of the car so as to normally urge said brackets and the rubber tired wheels thereon into firm engagement with the adjacent tracks 13. The springs 27 may have any desired tension, and the force exerted by them is sufficient to spread apart the wheels on opposite sides of the car and to force the rubber tires against their respective tracks 13 so that sufficient frictional contact is established between said tires and tracks to enable the car to travel up and down the tracks 13 of the shafts A, B and C when the wheels are driven in the proper direction and to hold the car at any desired attained level when the car is out of motion. This action of the springs in establishing and maintaining frictional engagement between the rubber tires and the tracks is supplemented by arranging the drive connection between the drive shaft of the motor and the driven shafts of the wheels so that the drive thrust is in a direction to force the shafts apart and to urge the wheels and tires toward their respective tracks 13. With such an arrangement, the cars are practically wedged between the opposite side walls of the shafts. A similar drive arrangement may be provided on the bottom of each car.

25   In the basement F' of the building, the shafts A, B and C are interrupted so as to form a space X, and the portions of the shafts disposed within the basement may be used as a storage space for the cars D. In the pent house F'', the shafts A, B and C are also interrupted to provide a space X', and the portions of the shafts in the pent house may be utilized as a storage space for cars D.

30   For the purpose of transferring the cars D from the "up" shaft A to the "down" shafts B and C, and from the shafts B and C to the shaft A, the cages G and the transfer mechanisms E are provided. Each of the cages is of more or less skeleton form and has tracks 13' which are adapted to be moved selectively into registry with the tracks 13 of the shafts A, B and C so that, in effect, when a cage is in position, the track sections 13' thereof form continuations of the track portions 13 of the shafts. The frame members of the cages are shown as comprising channel irons 60. Each cage is provided at its bottom with rollers or wheels 82 adapted to run on tracks 83. The transfer mechanisms E are

35   respectively disposed in the spaces X and X' and are of similar construction. In order to move the carrier into and out of registry with the shafts A, B and C, an eccentric arm 63 is pivotally secured, as at 64, to the side 60 of the carrier. The other end of the arm 63 is pivotally and eccentrically secured, as at 65, to a disk 66 which is mounted upon a shaft 67 carried by suitable bearings supported by a bracket 68. The shaft 67 is provided with a worm wheel 69 meshing with a worm 70 carried by a shaft 71 which is driven by an electric motor 72. It is noted from Figs. 1 and 4 that with this arrangement, the carrier may be moved from a position in registry with the shaft A to a position in which it is in registry with the shaft C.

40   In order to be able to move the carrier also into registry with the shaft B, the disk 66 and its motor 72 may be mounted upon a movable platform 73 to which is pivoted one end of an eccentric 74. The other end of the eccentric 74 is pivoted, as at 75, to a disk 76 rotatably mounted upon a bracket 77. The disk 76 may be connected by suitable gearing, not shown, to the drive shaft 78 of an electric motor 79. The movable platform 73 may be provided with flanged wheels 80 adapted to run on tracks 81.

45   In the use of the device, any number of cars D may be caused to move upwardly in the shaft A, one after the other in spaced apart relation and independently of one another. In order to effect the movement of a car D upwardly in the shaft A, the motors 25 may be started up and thus cause rotation of the wheels 20. Due to the action of the springs 27, the rubber tires on these wheels will be urged into firm frictional engagement with the tracks 13 of the shaft A so that they will cause the upward movement of the car D in the shaft A. This frictional engagement between the tracks 13 and the tires of the car D is augmented by the thrust of the drive connection between the motors 25 and the wheels of the car D, as pointed out above. The car D may be stopped at any desired floor by shutting off the motors 25, and each car may be equipped with a brake of the kind usually employed upon elevators. When the car D has reached the uppermost floor and the carriage of the upper transfer mechanism E has been moved to the position shown in Fig. 1 in which the carrier is in registry with the shaft A, the car D may be caused to move upwardly until it is disposed within the carrier. The motor 72 associated with the upper carrier may now be started up, and the disk 66 caused to rotate through substantially 180 degrees whereupon, due to the eccentric arm 63, the carrier will be moved into registry with the shaft C, which may be an "express down" shaft. If it is desired to return the car D to the lowermost floor by way of the shaft B, which may be a "local down" shaft, the platform 73 of the upper transfer mechanism E is caused to be moved towards the right, looking at Fig. 1, by means of the motor 79, disk 76 and eccentric 74, until the carrier is in registry with the shaft B. When the car D has been caused to be moved downwardly to the lowermost floor, the carrier of the lower transfer mechanism will be brought into registry with either the shaft B or C, depending upon whether the car has descended in the shaft B or C. The car D is then caused to enter the lower carrier which is then moved to a position in which it is in registry with the shaft A and the car D is again ready to ascend in the shaft A.

50   If it is desired to store cars in the basement, 55

55   60   65   70   75   80   83

60   65   70   75   80   83

65   70   75   80   83

70   75   80   83

75   80   83

when a car is brought down to the lowermost floor in either the shaft B or C, the lower carrier is aligned with either of these shafts, depending upon in which of these shafts the car has descended. 5 The car D is then caused to move through the carrier downwardly into either the lower portion of the shaft B or C. A car D may also be stored in the shaft A in the basement by moving the carrier with the car therein into registry with the shaft A and causing the car D to move downwardly thereinto. In a similar manner, cars may also be stored in the shafts A, B, and C in the pent house.

In the embodiment shown in Fig. 8, I have shown the invention applied to an installation 15 within a hill or mountain M. In this instance, there is shown, for illustrative purposes, the vertical shaft 100 at the lower end of which is a horizontal tunnel 101 leading to the side of the mountain. There are also shown supplemental vertical shafts 102 and 103, and supplemental tunnels 104, the latter being located at different levels. The cages and cars are shown diagrammatically. 20 With this arrangement, it is desirable to provide each cage or transfer carrier with its own motive power. For that purpose, the cage, as shown most clearly in Fig. 7, is provided with a small electric motor 105 connected by a belt 107 to a shaft 108 on which one pair of wheels 82' are secured. The horizontal tunnels are provided with tracks 83' 25 on which the wheels 82' travel. It will be seen that with this arrangement, the cages with the cars therein may be moved in the horizontal tunnels by energizing the motors 106. The vertical shafts 100, 102, and 103 are, of course, provided 30 with tracks 13 similar to those disclosed in the preceding embodiment.

As many changes could be made in the above construction and many apparently widely different embodiments of this invention could be made 40 without departing from the scope thereof, it is intended that all matter contained in the above description or shown in the accompanying drawings shall be interpreted as illustrative and not in a limiting sense.

45 It is also to be understood that the language used in the following claims is intended to cover all of the generic and specific features of the invention herein described and all statements of the scope of the invention which, as a matter of 50 language, might be said to fall therebetween.

I claim as my invention:

1. In combination, a pair of substantially parallel, vertically disposed elevator shafts each having opposed tracks, a transfer carrier disposed at one 55 end of said shafts and having track members adapted to respectively register with the tracks in said shafts, a car adapted to move in said shafts and having rubber tired wheels, means for urging said wheels into firm engagement with said tracks, 60 means for driving said wheels, and single stroke eccentric means associated with said transfer carrier for selectively moving the same into registry with said shafts.

2. In combination, a pair of substantially parallel vertically disposed elevator shafts, a plurality of parallel tracks disposed within said shafts at opposite sides thereof, a plurality of cars adapted 65 to ascend in one of said shafts in spaced apart relation and to descend in the other of said shafts, 70 a plurality of deformable rubber drive wheels carried by each car and resiliently engaging said tracks to support and propel the car thereon, means carried by each car for driving said wheels,

spring means for urging each of said wheels into deformed positive driving engagement with said tracks, and a single stroke eccentric means disposed adjacent each end of said shafts for transferring said cars from one shaft to the other. 5

3. An elevator installation comprising an elevator shaft, a plurality of opposed tracks therein, a car adapted to move in said shaft and having a wheel provided with a resilient deformable tread engageable with each track, means for maintaining each wheel in positive cushioned driving engagement with its respective track, and driving means associated with said car for rotating the wheels whereby the car will be moved smoothly and without vibration in the shaft. 10 15

4. In combination, a substantially vertically disposed elevator shaft having opposed tracks at the sides thereof, a car adapted to move within said shaft, a plurality of wheels journaled on said car and projecting therefrom, each of said wheels 20 being provided with a deformable non-slip rubber tread engageable with one of said tracks, means for yieldingly pressing said wheels into firm engagement with said tracks to support the car thereon and position it for free movement within the 25 shaft, and driving means associated with said wheels for rotating them and causing a smooth cushioned car movement within the shaft.

5. In combination, an elevator shaft having 30 tracks rigidly secured to the opposed sides thereof, a car adapted to move within said shaft and having wheels provided with cushioned rubber treads mounted in positive but resilient engagement with said tracks, means for resiliently urging said treads into positive anti-slip driving engagement with the tracks to support the car thereon, and power actuated driving mechanism on the car connected to transmit rotation to said driving wheels and control the car movement. 35

6. In combination, a substantially vertically 40 disposed elevator shaft, a plurality of tracks supported on opposed sides thereof, a car adapted to move within the shaft and having a plurality of wheels journaled thereon and mounted in frictional engagement with each of said tracks, each 45 of said wheels having a deformable rubber tread frictionally engaging a track, spring actuated means urging each of said wheels into positive non-slip engagement with its respective track, and means to transmit and control the rotation of 50 said wheels whereby the car may be moved within said shaft as desired.

7. In combination, a pair of parallel spaced elevator shafts, a plurality of parallel opposed tracks secured to the sides of said shafts, a transfer 55 carrier located intermediate of the ends of said shafts and movable in a direction opposed to that of the shafts, track members in the carrier similarly disposed to the shaft tracks, a car adapted to move in said shaft and into and out of the 60 transfer carrier, a plurality of wheels journaled on said car and extending outwardly therefrom, each of said wheels having a deformable anti-slip resilient tread engageable with a track, spring actuated mechanism on the car for maintaining 65 said wheels in positive driving engagement with the tracks, driving mechanism for rotating the wheels to control the car movement, and means to shift the transfer carrier into selective shaft registry whereby the car may be moved to operate in 70 either shaft.

JOHN T. AUSTIN.
